UNITED STATES PATENT OFFICE

WALTER L. RUTKOWSKI, OF ST. LOUIS, MISSOURI, ASSIGNOR TO R. C. CAN COMPANY,
OF ST. LOUIS, MISSOURI, A CORPORATION OF MISSOURI

CLOSURE FOR RECEPTACLES

Application filed March 28, 1927. Serial No. 178,983.

My invention relates to movable end closures for paper receptacles, or receptacles of other fibrous material known to the trade as paper cans.

5 The primary object of my invention is the provision of a metallic closure which when positioned on the open end of a receptacle by pressing it thereon by means of the fingers will be firmly held against accidental rotary 10 displacement and removal from the end of the receptacle.

A further object of the invention is to provide the closure with means for frictionally gripping the wall of the paper receptacle which naturally usually varies in gauge or thickness to prevent accidental removal of the closure therefrom.

The invention viewed in a more limited aspect aims to provide a metallic end closure 20 for paper cans having its side wall provided with a plurality of circumferentially spaced indentations to provide a plurality of inwardly directed protuberances for slight embedded engagement in the outer face of 25 the paper receptacle when positioned on the end of the receptacle to set up sufficient frictional resistance at several spaced points to firmly hold the closure in position, as against accidental rotary displacement and 30 removal.

A further object of the invention is the provision of a movable end closure for paper receptacles which possesses advantages in points of simplicity and efficiency, and, at 35 the same time proves itself comparatively inexpensive in cost of manufacture.

A practical embodiment of my invention is presented in the accompanying drawings forming a part of this specification and 40 wherein like characters of reference denote similar parts throughout the several views:

Fig. 1, is a side elevation of a paper receptacle having a removable end closure applied thereto embodying the feature of my 45 invention.

Fig. 2, is a vertical sectional view of the upper portion of the receptacle with the cover applied thereto.

Fig. 3, is a sectional view taken on line 50 3-3 of Fig. 1.

Fig. 4, is a bottom plan view of the closure.

Fig. 5, is a vertical sectional elevation of the closure with the indentations in the wall thereof exaggerated.

Fig. 6, is a detail showing the impressions formed in the outer face of the receptacle when applying the closure thereto.

Referring to the drawings, in detail, the reference character 1 represents an ordinary 60 paper receptacle, can, or tube having the usual fixed metallic bottom end closure 2, the opposite, or upper end of the receptacle being closed by the usual metallic slip cover, of closure 3 having the downwardly 65 directed flanged side wall 4 for frictional contact with the outer face of the receptacle.

In carrying out the aim of my present invention, I provide the side wall 4 of the metallic closure 3 with a plurality of circumferentially disposed unbroken indentations 5 which are formed upon the outer face of the wall 4 so as to provide a plurality of inwardly directed protuberances 6, which project inwardly beyond the inner face of 75 the wall 4 of the closure 3, as clearly illustrated in Fig. 5 of the drawings.

The side wall 4 of the closure 3 may have as many indentations 5 formed therein as desired and they may or may not be equally 80 spaced around the wall 4, as desired. The indentations 5 may be of any size, or shape desired, but are preferably formed by means of a conical pointed tool, although not necessarily limited thereto.

Heretofore removable metallic closures for paper receptacles fall off of the open end of receptacle very easily as they must of a necessity be made of such a size as to be easily and quickly applied to the open end 90 of all receptacles of the same outside diameter and which receptacles always vary slightly in outside diameter due to the variance in gauge of the paper stock used in forming the receptacles. The usual closure 95 will in some instances fit fairly tight when pressed into position, while on other receptacles of the supposed same outside diameter will fit loosely so that they will easily fall off of the receptacle, in shipment, in handling 100

and when placed so that it is moved about such as in tool boxes, especially, when the receptacles are used for containing tire patch material, which of course is only one class of goods which are packed in paper receptacles, thus it is not desired as being understood by that statement to be limiting myself to the use of the closure for packages containing only tire patch material, but that the closure is adaptable to any receptacle having a removable metallic closure for the open end of the receptacle.

From the foregoing description, it is evident that I provide a metallic closure especially adapted to paper receptacles, which due to the inwardly directed protuberances formed by providing the wall of the closure with a plurality of indentations upon its outer face will grip, or bite into the outer face 22 of the receptacle when positioning the closure upon the receptacle thereby slightly embedding themselves into the body of the receptacle for setting up sufficient frictional resistance to firmly hold the closure in position on the receptacle to prevent accidental removal of the closure from the receptacle from any cause.

From Fig. 6 of the drawing, it will be apparent that when the closure is pressed into 30 position upon the receptacle, that the protuberances of the closure will make slight impressions 7 in the outer face of the body of the receptacle for setting up the necessary resistance to prevent the closure from being 35 displaced or removed from the receptacle without the assistance of the fingers.

The many advantages of the herein described invention will readily suggest themselves to those skilled in the art to which it 40 appertains.

I do not wish to be understood as having limited myself to the exact details of construction shown and described, but desire to have it understood that the invention I have 45 shown in the drawings is merely illustrative, as it is manifest that various minor changes may be made in the exact construction and particular arrangement of parts without departing from the spirit of my invention, 50 hence I reserve the right to make any such changes, or modifications as may fairly fall within the scope of the appended claims when fairly construed.

What I claim is:

55. 1. In combination with a receptacle made of paper or other fibrous material which naturally varies in gauge, a metallic closure having a side wall for the open end of said receptacle and a plurality of cone shaped indentations formed in the wall of said closure before applying the closure to the receptacle to provide inwardly directed protuberances adapted for self embedded engagement with the outer face of the wall of the receptacle 60 when positioning the closure thereon.

2. An article of the class described comprising a tubular receptacle of paper or other fibrous material which naturally varies in gauge and having an open end, a metallic closure for the open end of said receptacle, 70 cone shaped resistance offering means formed upon the inner face of the side wall of the closure before the closure is positioned upon the receptacle for self embedded contact with the material of the body of the receptacle 75 when positioned thereon whereby the cover is removably but securely held in place against accidental displacement in any position upon the can.

3. An article of the class described comprising a tubular receptacle of paper or other fibrous material which naturally varies in gauge and having an open end, a metallic closure for the open end of said receptacle, a plurality of equally spaced circumferentially 80 disposed unbroken indentations formed in the outer face of the side wall of the closure before the closure is applied to the receptacle to provide a plurality of horizontally disposed conical protuberances directed inwardly beyond the inner face of the side wall of the closure for self embedded engagement in the material of the body of the receptacle by compressing the wall material when positioning the cover upon the receptacle whereby the 85 cover is securely held in place upon the receptacle but manually removable therefrom.

In testimony whereof I have hereunto affixed my signature.

WALTER L. RUTKOWSKI.
